UNITED STATES PATENT OFFICE.

CHRISTOPH FRIEDRICH BIRKENSTAMM, OF NEW YORK, N. Y.,
ASSIGNOR, BY DIRECT AND MESNE ASSIGNMENTS, TO PAUL
KURTZ, BRUNO NITSCHKE, FRITZ JAGAU, AND BERNHARD VON
REKOWSKY, OF NEW YORK, N. Y.

HOLDER FOR PADS.

SPECIFICATION forming part of Letters Patent No. 762,613, dated June 14, 1904.

Application filed January 27, 1904. Serial No. 190,783. (No model.)

To all whom it may concern:

Be it known that I, CHRISTOPH FRIEDRICH BIRKENSTAMM, a citizen of the Empire of Germany, residing in New York, borough of Manhattan, and State of New York, have invented 5 certain new and useful Improvements in Holders for Pads, of which the following is a specification.

This invention relates to an improved holder 10 for pads of that class which are used by waiters in hotels and restaurants for writing out the bills for the guests and the order-checks, said holder being so constructed as to support two different pads, a bill-pad to be left with 15 the guest for indicating his orders and the total amount of the same and an order paid for, controlling the waiter and the articles delivered to the guest, the object of the pad-holder being to enable the proprietor of the 20 hotel or restaurant to obtain a simple yet effective control of the waiters and the articles ordered by them from the different departments.

The invention consists of a holder for pads, 25 comprising two sections, each provided at one end with a rectangularly-bent-up portion, the upper top section being hinged to the edge of the bent-up portion of the lower or bottom section and each section being further provided in its bent-up portion with recesses for 30 the inwardly-projecting ends of flat pad-retaining springs for holding the pad on its respective section.

The invention consists, further, of certain 35 additional details of construction, which will be fully described hereinafter and finally pointed out in the claims.

In the accompanying drawings, Figure 1 is 40 a perspective view of my improved holder for pads, showing it in closed position. Fig. 2 is a perspective view of the same, showing it in open position. Fig. 3 is a vertical longitudinal section on line 3-3, Fig. 1; and Fig. 4 is a detail section on line 4-4, Fig. 3, showing the 45 hinge connection between the upper and lower sections when the holder is in open position, drawn on a larger scale.

Similar letters of reference indicate corresponding parts.

Referring to the drawings, *a* represents the 50 lower, and *b* the upper, section of my improved holder for pads. Both sections *a* and *b* are preferably made of equal size from oblong pieces of sheet metal, pasteboard, wood, or other suitable material and preferably covered with a layer of leather, paper, enamel, varnish, or similar material, so as to impart an attractive appearance to the holder. Each section *a* and *b* is provided at one end with rectangularly-bent-up portions *a'* and *b'*, respectively, said bent-up portions being provided with recesses *a²* *b²*, through which the bent ends *d* *e* of flat steel springs *d* *e*, the shanks of which are attached to the sections *a* and *b*, respectively, are extended so as to retain pads *f* 60 and *f'* on the upper and lower sections of the holder, respectively, as shown in Fig. 2. The pad *f*, which is placed on the lower section *a* of the holder, is retained at its end by the ends of the springs *d* and is made shorter than the pad 70 *f'*, that is retained on the upper section *b*, so as to differentiate the pads from each other and provide the required space for the inwardly-extending springs *e*. The individual sheets of the pad *f* are printed in suitable 75 manner so as to serve as order-checks for the waiters and covered by a carbon copying-sheet *f²*, while the pad *f'* is made, preferably, as large as the upper section *b* of the holder and intended to be used as a guest's bill-pad. The end of the upper section *b* opposite to its bent-up portion *b'* is hinged to the edge of the bent-up portion *a'* of the section *a*, as shown clearly in Fig. 2, so that the upper section can be placed in position 80 over the lower section, with its bent-up portion resting on the front end of the lower section, as shown in Fig. 1, or swung at an angle of one hundred and eighty degrees in backward direction, so as to rest by its rear end on 85 a table or other support. When the sections of the holder, with the pads in the same, are placed in closed position, the holder can be 90 readily carried in the pocket of the waiter,

while when the same is in open position for use it is placed on a table or other suitable support, so as to permit the waiter to remove the uppermost sheet of the pad f' , place it on the carbon-sheet of the waiter's order-pad, with the name and price of the dish ordered thereon, and then remove the order-check to be handed into the kitchen, bar, or other place. The guest's bill-check is then placed 5 on the guest's table, so that he can fully control the different articles ordered by and delivered to him. The guest's pad is firmly held on the upper section of the holder between the raised hinge connection with the lower section 10 b and the rectangularly-bent-up portion b' , as shown clearly in Fig. 2 and in cross-section in Fig. 4, so that it permits the ready removal of one check or slip after the other from the pad. The carbon-sheet a'' is permanently attached to the rear end of the pad a on the bottom section, so as to be always in proper position for placing the guest's check 15 thereon, so that the order is copied on the waiter's check below. The guest-check is then returned to the guest's table and the amount finally due obtained by adding up the sums thereon. The different departments to which the order-slips are delivered have a full control of the articles ordered by and delivered 20 to the guest, while the guest himself controls all along the articles which he has obtained and the amount of the charges for the same. 25

The individual sheets of the waiter's check-pad and guest's bill-pad may be printed in accordance with the control system for which they are used, the improved pad-holder serving for the purpose of holding the pads in a manner so as to be conveniently used by the waiter in writing the orders on the guest's 30 bill-check and duplicating them on the waiter's check below the carbon copying-sheet.

Having thus described my invention, I claim as new and desire to secure by Letters Patent—

45 1. A holder for pads, consisting of two sections hinged together, both sections being provided with a rectangularly-bent-up portion

at one end, the upper section being hinged to the bent-up portion of the lower section, and pad-retaining springs the bent ends of which 50 are attached to the upper and lower sections respectively and provided with bent ends extending through recesses in the bent-up portions of the upper and lower sections for retaining a pad in position on each section, substantially as set forth. 55

2. A holder for pads, consisting of a lower section provided with a rectangularly-bent-up portion at its end, an upper section hinged at one end to the bent-up portion of the lower section and provided with a rectangularly-bent-up portion at its opposite end, flat springs attached to the lower and upper sections respectively and extending with their free bent ends through recesses in the bent-up portions 60 of the lower and upper sections, and pads retained by said springs on the lower and upper sections respectively, substantially as set forth. 65

3. A holder for pads, consisting of a lower section provided with a rectangularly-bent-up portion at its end, an upper section hinged at one end to the bent-up portion of the lower section and provided with a similar rectangularly-bent-up portion at its opposite end, flat 70 springs attached to the lower and upper sections respectively and extended by their free bent ends through recesses in the bent-up portions of the lower and upper sections, and pads supported by said springs on the upper 75 and lower sections respectively, the pad supported on the lower section being shorter than the pad supported on the upper section, the latter being retained between its bent-up end and the raised hinge connection of the lower section, substantially as set forth. 80

In testimony that I claim the foregoing as my invention I have signed my name in presence of two subscribing witnesses.

CHRISTOPH FRIEDRICH BIRKENSTAMM.

Witnesses:

PAUL GOEPEL,
HENRY J. SUHRBIER.
